UNITED STATES PATENT OFFICE

FRANK MARIANI, OF NEW YORK, N. Y., ASSIGNOR TO WM. DEMUTH & CO., OF NEW YORK, N. Y., A CORPORATION OF NEW YORK

DESIGN FOR A BODY FOR A PORTABLE CIGAR AND CIGARETTE LIGHTER

Application filed November 20, 1929. Serial No. 33,509. Term of patent 3½ years.

To all whom it may concern:

Be it known that I, FRANK MARIANI, Italian citizen, residing at State, county, and city of New York, have invented a new, original, and ornamental Design for a Body for a Portable Cigar and Cigarette Lighter, of which the following is a specification, reference being had to the accompanying drawing, forming part thereof.

I claim:

The ornamental design for a body for a portable cigar and cigarette lighter as shown.

In testimony whereof, I affix my signature.

FRANK MARIANI.
